US00D925991S

(12) **United States Design Patent** (10) **Patent No.:** **US D925,991 S**
(45) **Date of Patent:** **** Jul. 27, 2021**

(54) **CONTAINER ACCESSORIES**

(71) Applicant: **YETI Coolers, LLC**, Austin, TX (US)

(72) Inventors: **Steve Charles Nichols**, Austin, TX (US); **Andy Bondhus**, Austin, TX (US); **Tobias Hotchkiss**, Austin, TX (US); **Mark Carlson Rane**, Austin, TX (US); **John Loudenslager**, Austin, TX (US); **Derek G. Sullivan**, Austin, TX (US)

(73) Assignee: **YETI Coolers, LLC**, Austin, TX (US)

(**) Term: **15 Years**

(21) Appl. No.: **29/760,880**

(22) Filed: **Dec. 4, 2020**

Related U.S. Application Data

(63) Continuation of application No. 29/757,384, filed on Nov. 5, 2020, which is a continuation of application (Continued)

CLAIM

The ornamental design for container accessories, as shown and described.

DESCRIPTION

FIG. 1 is a top, front, right perspective view of container accessories showing our new design;

FIG. 2 is a top view thereof;

FIG. 3 is a top, front, right perspective view of a divider accessory of container accessories showing our new design;

FIG. 4 is a bottom, rear, left perspective view of the divider thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines immediately adjacent to the shaded area define the bounds of the claimed design and form no part thereof. The broken lines depicting the remainder of the container accessories show features that form no part of the claimed design.

1 Claim, 8 Drawing Sheets
